CLAIM

The ornamental design for a double knotted braided rope pet toy, as shown and described.

DESCRIPTION

FIG. 1 is a perspective view of a double knotted braided rope pet toy embodying my new design;
 FIG. 2 is a front elevation view thereof;
 FIG. 3 is a rear elevation view thereof;
 FIG. 4 is a right side elevation view thereof;
 FIG. 5 is a left side elevation view thereof;
 FIG. 6 is a top plan view thereof; and,
 FIG. 7 is a bottom plan view thereof.

The broken lines depict environmental subject matter, are for illustration only and form no part of the claimed design.
